UNITED STATES PATENT OFFICE.

WALTER L. HUTCHINSON, OF HARTFORD, CONNECTICUT, ASSIGNOR TO THE SKAYEF
BALL BEARING COMPANY, A CORPORATION OF CONNECTICUT.

ANTIFRICTION-BEARING MOUNTING.

Application filed July 20, 1921. Serial No. 486,108.

To all whom it may concern:

Be it known that I, WALTER L. HUTCHINSON, a citizen of the United States, residing at Hartford, in the county of Hartford and State of Connecticut, have invented certain new and useful Improvements in Antifric-
5 tion-Bearing Mountings, of which the following is a specification, reference being had therein to the accompanying drawing.

10 This invention relates to anti-friction bearing mountings, and more particularly to the mounting of ball bearings in precision machinery especially that involving a rotary spindle. An illustrative example of an in-
15 stallation to which my improvement is pec-
uliarly adapted is a spindle normally rotat-
ing at high speed and carrying a working
tool which comes into engagement and leaves
the work while rotating rapidly.

20 A basic principle of the invention is em-
bodied in mechanism whereby the bearings, which if desired may be ball bearings, sup-
porting the spindle adjacent the work per-
forming portion, as for instance that carry-
25 ing the grinding wheel or other rotary tool,
are continuously under initial load in the
direction of the working load, that is, the
spindle is loaded or pressed in the direction
of the pressure applied to it by its work, but
30 materially in excess of such pressure to the
end that there is no movement or tendency to
movement of the spindle or the tool carried
thereby upon its engagement with the work,
and upon its leaving the work. An advan-
35 tage of this is that the tool, as for instance,
a grinding or polishing tool which has but a
light engagement with the workpiece, may
be presented to the work in such a manner
that it does not in the initial application
40 yield away from the work, which yielding
causes chattering, and when it leaves the
work does not move back toward the work,
which movement, when it occurs, again
causes chattering and marring of the finish
45 produced by the tool. The tool carried by a
spindle mounted according to my invention
has a constant position relative to its sup-
port and does not have a normal running
idle position different from the working
50 position.

In the drawings accompanying this appli-
cation there is shown, by way of illustration,
a practicable embodiment of the invention
wherein the improved mounting is applied

to the high speed spindle of a grinding ma-
chine, such spindle being shown mounted in
a "quill," in which drawings—

Figure 1 is a section taken axially of the
spindle, and

Fig. 2 is a cross section taken on a plane
at about the line 2—2 of Figure 1.

The spindle 5, in the present illustration,
is intended to be rotated at high speed by
means of some suitable device, as for in-
stance, a belt running upon pulley 6, and
carries, as a working tool, a grinding wheel
7. The particular wheel illustrated is
adapted for grinding the inner surface of a
ring 8, such ring being in practice held in
a suitable rotary chuck, the kind of grinding
contemplated by this particular installation
being effected not only by a rotation of the
grinding wheel, but also an oscillation there-
of imparted to the wheel from the casing or
"quill" 9 which is mounted on a suitable
oscillatory base, not shown.

At the back or pulley end of the spindle
there is shown suitable anti-friction support
in the form of a bearing 10 fast to the spin-
dle and mounted for axial movement in the
quill, this being a common form of mounting
needs no particular explanation.

It is quite necessary to rigidly support the
front or wheel carrying end of the spindle,
not only during its working period, but
while it is approaching and coming into en-
gagement with the work and while it is leav-
ing the work and receding therefrom.
When bearings are mounted initially tight,
this object is attained for a short time, but
only for a short time, and owing to the wear-
ing down of the parts of the bearing, which
in many instances is little more than a pol-
ishing action, there is introduced a sufficient
looseness to overcome the original accurate
fit. This looseness necessitates tightening
the bearings. This has been accomplished
in various ways, generally in some manner
which requires the demounting of the spin-
dle and the disassemblage of the entire ball
bearing construction. According to my in-
vention, however, the initial tightness and
the maintenance of tightness may be had
without removing any of the parts or open-
ing the interior if the quill, it also takes care
of bearing tightness as well as any slight
looseness in fit of the outer races in their
housing and effects of deflection of material.

Adjustment is capable of being effected while the spindle is running and the tool operating upon the workpiece.

To accomplish the adjustment and to afford a wide supporting base for the front end of the spindle I mount upon it a plurality of bearings. In the illustration there are shown three two-row self-aligning bearings, A, B, and C, the inner races a , b , c , of which are locked against the shoulder 11 of the spindle by means of a suitable nut 12. The outer races, a' , b' , c' of the bearings, are so mounted in a housing formed in the quill that the ring b' of the intermediate bearing 15 of the three has its edges or sides free from the sides of the rings a' and c' which are disposed laterally of it. In closing up the casing the cap 13 is tightened against a shoulder 14 allowing a distance between the inside face 15, of the cap which engages the outer ring of the first bearing A, and the shoulder 16, for the inner bearing C, equal of the width of three normal outer races. The sides of the race b' having been lapped off a small amount, it is free to move radially relatively to the rings upon its respective sides. The bearing housing portion of the quill is provided with a chamber 17 which is formed as a groove so that the bearing B may move radially, the side bearings A and C, of course, being held from such radial movement.

At the work engaging side of the spindle a cradle 18 is mounted, which is in the form of a segmental shoe located in the chamber 17, and supporting the ring b' . A set screw 19 engages this cradle, and is located in position for forcing the cradle, and the bearing resting therein, in a direction parallel with the working load of the grinding wheel. Preferably the cradle or shoe is relieved opposite the set screw as at 20. This adds a certain amount of elasticity to the device and moderates the rigidity and harshness which might, otherwise, be found destructive to the bearings in some installations.

Adjustment of the bearings to take up slack and tighten them in the working direction is accomplished by screwing in the set screw 19 thereby moving the bearing supported by the cradle, and with it the spindle 5, in the direction which it tends to move owing to this working load. Preferably the load placed upon the said bearings by means of this adjustment is in excess of any load which will be placed upon the spindle by its work. This set screw is preferably made quite small to safeguard the bearings against unskillful adjustment, thereby presenting a construction the care of which need not necessarily be specially entrusted to highly skilled machine operators.

It is to be understood that the example shown herein while embodying a preferred form of construction is illustrative of the in-

vention, and that changes in details may be made as occasion demands, within the scope of the claims, without departing from the spirit of the invention.

I claim as my invention—

1. The combination with a spindle, of a mounting therefor comprising a housing and three anti-friction bearings, and means for applying pressure to the intermediate bearing.

2. The combination with a spindle, of a casing therefor, a pair of anti-friction bearings housed in the casing and supporting the spindle, a bearing intermediate these bearings and mounted on the spindle, the outer portion of this bearing being circumferentially free of the housing, and pressure applying means engaging said intermediate bearing.

3. A bearing mounting comprising a spindle and a casing therefor, a plurality of anti-friction bearings mounted upon the spindle and housed in the said casing, and means for applying radial pressure to one of the said bearings for applying initial tension to the other bearings of the set in the direction of the working pressure to which the spindle is adapted to be subjected.

4. A spindle adapted at one end for carrying a working tool, a housing in the form of a quill surrounding the spindle, three bearings provided with rolling elements located within the quill and mounted upon the tool carrying end of the spindle, and means active upon the centrally located bearing for applying pressure to the spindle in the direction of the line of reaction from the tool engagement with its work.

5. The combination with a spindle adapted at one end to carry a working tool, of three anti-friction bearings provided with rolling elements mounted upon said spindle adjacent the tool carrying end, the inner races being locked together and the outer races being out of engagement one with the other, a casing surrounding said bearings and affording a housing having a fit with the outermost bearings and free of the outer ring of the innermost bearing, and means for engaging the outer ring of the intermediate bearing and applying pressure thereto in a radial direction.

6. The combination with a spindle, of three annular ball bearings located thereon, a quill surrounding the spindle and provided with a housing for the outer rings of the ball bearings, said housing being chambered out radially of the outer ring of the intermediate bearing, such ring being free of the rings of the laterally disposed bearings, a cradle located in the chamber portion of the housing and engaging the outer ring of the intermediate bearing, and means for pressing the said cradle against such ring.

7. The combination with a spindle, of

three annular ball bearings located thereon, a quill surrounding the spindle and provided with a housing for the outer rings of the ball bearings, said housing being 5 chambered out radially of the outer ring of the intermediate bearing, such ring being free of the rings of the laterally disposed bearings, a cradle located in the chamber portion of the housing and engaging 10 the outer ring of the intermediate bearing, the cradle being a segment of less than half a circle and at its ends embracing the ring, it being relieved at the center portion and a set screw carried by the quill and engaging 15 the center portion of the cradle opposite the relief.

8. In a high speed spindle, the combination with a spindle having a working end and a driven end, of a quill surrounding the 20 spindle and from the ends of which the ends of the spindle project, ball bearing support for the spindle at the driven end, three ball bearings mounted at the work end, the inner rings of the said ball bearings being 25 clamped together on the spindle, the quill at such end being formed with a housing adapted to engage in a suitable manner the outer rings of the laterally disposed bearings and being chambered out radially of the 30 outer ring of the intermediate bearing, such ring being free of the laterally disposed bearings, and a closure for the end of the quill having a suitable opening for the projecting work end of the spindle and 35 adapted to engage the outer ring of the outermost lateral bearing, there being provided stop shoulders for limiting the closing movement of such closure whereby sufficient space is provided for permitting the 40 aforementioned freedom between the sides

of the outer rings, and means for moving the outer ring of the intermediate bearing radially.

9. The combination with a spindle, of a casing therefor, an anti-friction bearing 45 housed in the casing and supporting the spindle, a bearing adjacent thereto and mounted on the spindle, the outer portion of this latter bearing being circumferentially free of the housing, and pressure applying 50 means engaging said latter bearing.

10. A spindle adapted at one end for carrying a working tool, a housing in the form of a quill surrounding the spindle, bearings provided with rolling elements located within the quill and mounted upon the tool carrying end of the spindle, and means active upon one of the bearings for applying pressure to the spindle in the direction of the line of reaction from the 60 tool engagement with its work.

11. The combination with a spindle adapted at one end to carry a working tool, of anti-friction bearings provided with rolling elements mounted upon said spindle adjacent the tool carrying end, the inner races being locked together and the outer races being out of engagement one with the other, a casing surrounding said bearings and affording a housing having a fit with the 70 outer ring of one of the bearings and free of the outer ring of another of the said bearings, and means for engaging the outer ring of the latter bearing and applying pressure thereto in the direction of the working 75 pressure to which the spindle is adapted to be subjected.

In testimony whereof, I have affixed my signature hereto.

WALTER L. HUTCHINSON.
